United States Patent Office.

CYRUS SMITH, OF HERMON, MAINE.

Letters Patent No. 86,255, dated January 26, 1869.

RAILROAD-CAR HEATER.

The Schedule referred to in these Letters Patent and making part of the same.

To all whom it may concern:

Be it known that I, CYRUS SMITH, of Hermon, in the county of Penobscot, State of Maine, have invented a new and improved Stove for Cars; and I do hereby declare that the following is a full, clear, and exact description thereof, reference being had to the accompanying drawings, in which—

Figure 1 is a central longitudinal vertical section through line *a b* of fig. 2.

Figure 2 is a transverse vertical section through line *x y* of fig. 1.

The object of my invention is to produce a stove for use in railroad-cars, so constructed as to avoid the danger of conflagration by the upsetting of the stove, whenever an accident occurs, overturning or partially overturning the car.

My invention has been suggested to me by the numerous painful accidents which have recently occurred on various railways, where the suffering and loss of life and limb have been greatly increased by the conflagration which has ensued from the overturning of heated stoves.

Inventions have been made to provide against such successive calamities, but they do not effectually accomplish the purpose sought.

Cost is not so much of an object, in an invention of this nature, as effectiveness in at once extinguishing the fire in the stove, immediately on its overturning, or even turning on its side.

The nature of my invention consists in providing means for securely retaining the fire, cinders, and coals within a railroad-car stove, when used in combination with a reservoir of water under the fire-box, and extending beyond the surface of the bottom of the fire-box, on all sides, the reservoir so connected with the stove that it shall not interfere with the practical use of the stove in the ordinary manner, but which will empty its contents upon the fire, on the stove being overturned, either wholly or partially, and not only deluge the fire with water, but that the water shall be retained within the enclosure of the fire-box, thus completely preventing any conflagration.

In the drawings—

A represents fire-box, open at top.

B, a box, larger than fire-box, which shuts over or encloses *A*, leaving space, *S*, on sides, back, and top of fire-box, but not in front.

C is a tank or reservoir, under the fire-box *A* and cover *B*, projecting on all sides beyond the surface of *B*, or it may be of same size at bottom surface of *B*.

D is a grate.

E is the funnel.

h h are automatic valves or slides, which move in inclines *L*.

K is the top of reservoir *C*.

This is provided with holes, *F*, between fire-box *A* and outside box *B*.

m is the valve or water-hole, for supplying the reservoir.

i is a stop-cock, or any means by which water can be withdrawn from the reservoir.

H is the door of the stove.

Water contained in reservoir *C* cannot be heated

much above blood-heat, on account of its position below the fire, the space between the fire and the top of the reservoir, and the fact that there is no direct communication between fire-box *A* and reservoir *C*. This construction, then, avoids the continual generation of steam, as must take place when the water-tank is over the fire, for heated air rises.

There being no direct communication from fire-box *A* to the reservoir, there can be no difficulty arising from the ashes falling into the reservoir. Again, the influence of top *K*, on the surface of the water, prevents any slopping through *F* by the ordinary jar of the stove.

Now, if this stove, with a fire burning within it, and the tank filled or partially filled, is overturned, or falls upon its side, the water at once forces itself, by its own weight, through the holes at *F*, flooding the whole space *S* and fire-box *A*, which, being open at its top, discharges its contents into *S*. When the stove went over, one of the slides or valves *h h* closed by its own weight, thus shutting the funnel-hole *E*, so that no water or fuel would escape therefrom. This action is essential, for if funnel *E* were left free, the danger would not be overcome, and this closing of *E* also secures a complete flooding of the fire, effectually extinguishing it.

The sliding valves *h* run on inclines, one sliding in one direction, the other in the other, so that no matter which way the stove falls, one or the other slide or valve, by its own weight, slides into place and closes *E*; nor is there any liability of these slides closing *E* from the ordinary jarring of the car, as they run in inclines, and it requires nearly as much slant of the stove to close them as would be required to throw the fire out of the box *A*.

The door *H* is constructed in any suitable manner, with the necessary openings for draught.

There is no danger from explosion when a stove is overturned, as has been described, for the draught-holes are sufficient for the necessary escape of gases formed by the heating of the water.

I do not claim any particular construction of the body of my stove, nor a water-tank under a railroad-car stove; nor do I claim, broadly, the use of a guard over the mouth of the collar, as these devices have already been used; but

What I claim as new, and desire to secure by Letters Patent, is—

1. The sliding valves *h h*, acting in inclines *L*, for the purpose described, in combination with box *B* and reservoir *C*, substantially as and for the purposes set forth.

2. The reservoir *C*, constructed as described, in combination with box *B*, open-top fire-box *A*, and sliding valves *h h*, the whole constructed and operating substantially as and for the purposes set forth and described.

In testimony whereof, I have signed my name to this specification, in the presence of two subscribing witnesses.
